Specification for Design.

Patented Jan. 5, 1915.

Application filed October 6, 1914. Serial No. 865,388. Term of patent 14 years.

To all whom it may concern:

Be it known that we, LEON O. FISHER and COMO D. MASSEY, both citizens of the United States, and residents, respectively, of Yonkers, in the county of Westchester and State of New York, and Upper Montclair, in the county of Essex and State of New Jersey, have invented a new, original, and ornamental Design for a Desk, of which the following is a specification, reference being had to the accompanying drawing, forming part thereof.

Figure 1 is a perspective view of a table showing my new design; Fig. 2 is a perspective view of a desk showing my new design, the same being taken from the opposite side to that shown in Fig. 1.

We claim:

The ornamental design for a desk, as shown.

LEON O. FISHER.
COMO D. MASSEY.
